COMBINED CLOSURE AND APPLICATOR

Charles G. Yates, Greensboro, N. C., and Wallace W. De Laney, New Haven, Conn., assignors to Vick Chemical Company, Philadelphia, Pa., a corporation of Delaware

Application January 18, 1935, Serial No. 2,436

3 Claims. (Cl. 221—148)

This invention relates to a combined closure and applicator of the general character used primarily but not necessarily for medicines, such as are applied drop by drop to the nose and/or throat.

It is usual in the distribution of medicaments intended for application to the nose and throat to sell a bottle of the liquid closed by a screw cap and to furnish with such bottle a combination stopper and dropper for use with the bottle by the person using it, the original screw cap being thrown away and the combination stopper and dropper being subsequently used as both a bottle closure and applicator.

It is aimed to produce a construction of the class having a rigid cap, elastic bulb and rigid dropper which remains exceedingly simple, inexpensive and durable, wherein relative movement between the elastic bulb and cap is overcome, wherein the unsatisfactory frictional holding of the elastic part and cap is obviated enabling a more unitary use and operation of the elastic part and cap unaffected by the oily content of such a medicine, and to provide a construction which overcomes the likelihood of separation of the cap and elastic part through usage.

A primary object is to provide in such a device, a cap having its top wall centrally open and upwardly and inwardly bulged to more effectively coact with an exterior protuberance on the elastic bulb to avoid or guard against a relative movement between the cap and elastic member.

The more specific objects and advantages will become apparent from a consideration of the description following, taken in connection with the accompanying drawing illustrating an operative embodiment.

In said drawing:

Figure 1 is an enlarged view in central vertical section, showing the invention applied to a bottle or container;

Fig. 2 is a top or plan view of the invention; and

Fig. 3 is a detail perspective view of the bulb or elastic part.

Referring specifically to the drawing wherein like reference characters designate like or similar parts, the invention essentially comprises a closure cap 10, a one piece rubber or other elastic element 11, and a dropper tube 12 carried by the latter, all constituting a unit adapted for application and removal to or from a bottle or container 13.

Said cap 10 may be made of any suitable relatively rigid material, for instance, sheet metal, and has screw threads at 14, engaging correspond-

ing screw threads at 15 on the neck of the bottle 13.

Said cap 10 has an upper wall 16 which has a central opening at 17 and which wall is upwardly and inwardly bulged by doming or curving the 5 same as shown.

In constructing the metal cap 10, the top 16 thereof extends inwardly in a horizontal plane as at 16' and is then bulged or domed slightly upwardly as at 16'', after which the wall or top 10 16 again extends inwardly in a horizontal plane as at 16'''.

The elastic body 11 is preferably made in a single piece and has a bulb 18 which extends snugly through the aforesaid opening 17, and a basal flange 19 extending outwardly and disposed under and marginally engaging the top wall 16 of the cap. In addition, the bulb 18, slightly above its basal flange 19 has an exterior lateral protuberance 20, such as an annular rib as shown, 20 which engages the outer surface of the wall 16.

The vertical distance between the plane of the two portions 16' and 16''' is slightly greater than the width of the space between the lower portion of the annular rib 20 and the upper portion of the 25 flange 19.

In assembling the device the dropper tube is inserted in the elastic member or bulb 18 and then pulled upwardly through the aperture 17 until the rib 20 has passed through said aperture 30 and become seated above the portion 16''' of the cap 10. As a result the wall 16 about the opening 17 is gripped by the flange 19 and protuberance 20 preventing any material relative movement between the elastic body 11 as a whole and the cap 10.

The results sought are attained even with clearance provided between the upper surface of the basal flange 19 inwardly of its margin as shown at 21. The peripheral edge of the basal flange 19 does not contact the side wall of the cap 10 since these parts are held together otherwise than by friction, and also since there will be less suction to overcome in removing the device from the bottle.

Relative bodily movement between the elastic element 11 and the cap is further prevented by inwardly extending the flange 19 as at 22 about the entrance to the bulb, and which flange 22 snugly snaps into a continuous groove 23 provided about the dropper tube 12 adjacent the top thereof. Such dropper tube 12 may be made of any suitable material, usually of glass.

The invention is primarily used in connection with a medicine contained within the glass or 55

other bottle or receptacle 13, for instance of that oily character which is applied drop by drop to the nose and throat. To this end, the bulb 18 is compressed to draw the medicine into the dropper tube 12, while the cap 10 is detached 5 from the bottle 13; release of the bulb permitting it to expand to the normal condition shown and to thereby eject the medicine.

It will be realized that when the dropper is not 10 being used to apply the medicine, flange 19, by reason of its engagement with the upper edge of the bottle 13, forms an effective seal.

To facilitate manipulation of the device, the 15 cap 10 at the side above the screw threads 14 is preferably knurled as shown at 24.

Various changes may be resorted to provided 15 they fall within the spirit and scope of the invention.

We claim as our invention:

- 20 1. In combination, a closure cap having an upwardly bulged upper wall provided with a central opening, an elastic element having a bulb disposed in said opening and a laterally extending flange having a bottle-neck sealing portion beneath said wall, said wall being spaced from said flange adjacent said bulb, a protuberance 25 on said bulb exteriorly of the cap gripping said wall jointly with said flange, and a dropper tube

carried by the flange in communication with said bulb.

2. In combination, a closure cap having an upwardly bulged upper wall provided with a central opening, an elastic element having a bulb disposed in said opening and a laterally extending bottle-neck sealing flange beneath said wall, a continuous protuberance on said bulb exteriorly of the cap gripping said wall jointly with 5 said flange, said flange having a portion extending inwardly at the entrance to the bulb, and a dropper tube having an external groove engaged by said inwardly extending portion of the flange.

3. In combination, a closure cap having an upper wall provided with a central opening, an 15 elastic element having a bulb disposed in said opening and a laterally extending flange having a bottle-neck sealing portion beneath said wall and engaged therewith about the margin of the flange, a continuous protuberance integral with 20 said bulb exteriorly of the cap overlapping said wall about said opening, and a dropper tube extending through and carried by the flange in communication with said bulb, said flange adjacent the opening of the cap being spaced from 25 said wall when the margin of the flange is in contact with said wall.
